(57) **CLAIM**

The ornamental design for an emergency alert light, as shown and described.

DESCRIPTION

FIG. 1 is a perspective view of an emergency alert light showing our new design, wherein the transparent covering raised above the grid is demarcated by the special surface marking.

FIG. 2 is a front view thereof;

FIG. 3 is a back view thereof;

FIG. 4 is a side view (opposite side view is mirror image) thereof;

FIG. 5 is a top view thereof; and,

FIG. 6 is a bottom view thereof.
